UNITED STATES PATENT OFFICE.

FREDERICK SEABERG, OF CHICAGO, ILLINOIS, ASSIGNOR TO NATIONAL DUMP CAR COMPANY, OF CHICAGO, ILLINOIS, A CORPORATION OF MAINE.

DUMP-CAR.

953,182.

Specification of Letters Patent. Patented Mar. 29, 1910.

Application filed December 26, 1907. Serial No. 408,031.

To all whom it may concern:

Be it known that I, FREDERICK SEABERG, a citizen of the United States, residing at Chicago, in the county of Cook and State of Illinois, have invented certain new and useful Improvements in Dump-Cars, of which the following is a specification.

The object of my invention is to provide an improved door operating mechanism especially adapted for that type of dump cars having drop doors in the bottom thereof, and also to provide an improved cover plate at the center of the car adapted to prevent the contents of the car from entering the space behind the hinged edge of the door.

In the drawings—Figure 1 is a cross section of so much of a floor of a dump car as is necessary to illustrate my improvements. Fig. 2 is a plan view of the central part of one of the cross beams showing my improved cover plate. Fig. 3 is a side view of the center sill showing the supports for the door hinges and my improved cover plate, together with the means of attaching the same to the remainder of the car structure.

My improvement is especially adapted for use in that type of cars wherein the dump doors, or hinged floor sections are operated by means of a transversely movable shaft, such as that designated by the numeral 1 upon the drawing. In cars of this type the transversely movable shaft moves upon a guide rail which extends transversely of the car from the outer edge toward the center. The outer part of this rail is usually horizontal in order that the door may be firmly supported when the transversely movable shaft is in its outer position. A car having a track rail of this general type is illustrated in the patent to Otis No. 823,631, July 19, 1906. The guide-rail slopes downwardly from the side of the car toward the center, thus permitting the door to drop when the shaft is moved toward the center of the car.

In practice it has been found that the guide-rail sometimes meets with injury owing to its exposed position, sloping downwardly as it does below the floor of the car. The guide-rails located near the ends of the car over the trucks must be constructed to leave about two inches clearance between them and the arch bars of the truck side frames, as the settling of the car upon the springs would cause the guide-rails to contact with the arch bars unless sufficient clearance were

left, thus causing the load of the car to impose a strain on the guide rails which they are not calculated to withstand. As all the guide-rails throughout the length of the car must be constructed in the same plane, the extent to which the guide-rails can project downwardly is limited by the form of the guide rails over the trucks. It is to obviate these disadvantages, and to provide an improved cover plate between the inner edges of the door along the center of the car that my improvements are designed.

In the structure illustrated in the drawings the central longitudinal support or center sill of the car consists of two channel irons 2, spaced apart and connected at intervals by plates 3. Supported by the center sill 2 are cross beams 3' reinforced at their upper edges by channel irons 4. The cross beams 3' are secured to the center sill 2 by means of angle irons. Sloping inwardly and upwardly from the outer sides of the center sill and riveted to the flanges of the channel irons 2 are supports 6, and extending longitudinally of the center of the car are T-irons 7. The downwardly extending web of each of these T-irons is secured between the upper ends of the members 6 by means of rivets and the top of the T-iron 7 is flush with the upper surface of the cross beam 3' and its reinforcing angles 4. The T-iron 7 forms a cover plate projecting over the inner hinged edges of the doors 9. The T-iron cover plates 7 are constructed in sections, each section extending between two adjacent cross beams, and the T-irons 7 are not only supported by the inclined members 6, but are also secured to the cross beams 3' by means of angles 10, which are riveted to the T-irons and through the cross beams 3' and their reinforcing angles 4. The doors 9 are, in the present instance, provided with pintles 11 which coat with hinge members 12 riveted to the inclined support 6. The relation of the inner edges of the doors and the cover plates 7 is such that the cover plate extends over the inner edges of the doors both in open and closed position.

Fixedly secured to the car at the side thereof is a fixed member 14 forming the outer part of the support for the transversely movable shaft 1. The upper surface of the part 14 at the point 15 is substantially horizontal in order that the shaft may have no tendency to roll inwardly and

permit the door to open after it has been moved to closed position. The inner inclined part of the support for the shaft 1 instead of being formed as a rigid or integral part of the car structure takes the form of a pivoted guide-rail 16, which by means of the mechanism hereinafter described may assume either the position shown in dotted lines in Fig. 1, or that shown in solid lines. The guide-rail 16 is connected near its outer end by a pivot 17 with the inwardly extending part of the support 14, and its outer end projects beyond said pivot and is so formed that when the transversely movable shaft 1 is moved to its outer position it contacts with said outwardly extending free end of the guide-rail 16, thus depressing said outer end and raising the inner end from the position shown in dotted lines in Fig. 1 to that shown in solid lines. When the guide-rail 16 is in its lower position, that illustrated in dotted lines in Fig. 1, it is supported by means of a link 18 pivoted to the cross beam at 19 or to some other fixed part of the car underframe. In order to permit the guide-rail 16 to move to its upper position the lower end of the link 18 is connected thereto by means of a pin and slot connection. In the present instance, the slot is formed in the link 18 and the pivot pin 20 passes through said slot and is secured to the inner end of the track rail.

It will be observed that when the transversely movable shaft is moved from the position shown in dotted lines in Fig. 1 it will coat with the track 16 and the inclined guide-rail 25 causing the door to rise to closed position, and that when said shaft 1 reaches the rigid part 14 of its support it will contact with the outwardly extending free end of the guide-rail 16, thus depressing said outer end and raising the inner end to the position shown in solid lines in Fig. 1. By means of this construction the guide-rail 16 may be so formed that in the lower position it will come practically down to the arch bars of the truck frames, there being no danger of breakage upon depression of the car under its load, for the reason that in my improved construction the track rails could yield upon their pivots under such pressure. It is, therefore, possible to secure an increased movement of the doors and a larger door opening, thus securing a more effectual dumping of the contents of the car.

What I do claim is:

1. In a car, a door, a hinge therefor, an operating member movable transversely of

the door, and a movable rail adapted to support said operating member.

2. In a car, a door, a hinge therefor, an operating member movable transversely of the door, a movable rail adapted to support said operating member, and means to move said rail toward said door when the latter is moved to closed position.

3. In a car, a door, a hinge therefor, an operating member movable transversely of the door, a movable rail adapted to support said operating member, and means whereby the movement of said operating member to close the door raises said movable rail.

4. In a car, a door, a hinge therefor, an operating member movable transversely of the door, a support therefor comprising a fixed part and a movable guide-rail, and means whereby the movement of said operating member to close the door raises said guide-rail.

5. In a car, a door, a hinge therefor, an operating member movable transversely of the door, a support therefor comprising an outer fixed part and a guide-rail pivoted thereto and having a free end extending beyond the pivot to a position where said operating member upon being moved to its outer position will contact said free end and raise said guide-rail.

6. In a car, a door, a hinge therefor, an operating member movable transversely of the door, a support for said operating member comprising an outer fixed part and a guide-rail pivoted thereto, and a link pivoted at one end to a fixed part of the car and engaging the inner end of said guide-rail.

7. In a car, a door, a hinge therefor, an operating member movable transversely of the door, a support therefor comprising an outer fixed part and a guide-rail pivoted thereto at one end, a link pivoted to a fixed part of the car and to the inner end of said guide-rail, said link having a sliding movement on one of said pivoted connections.

8. In a dump car, a central longitudinal support, transverse supports above and resting on said central support, inclined members sloping upwardly and inwardly from said central support, a T-iron cover-plate at the level of the upper part of said transverse supports, said T-irons being secured to and supported by said inclined members and transverse supports, and doors hinged beneath the flanges of said T-iron cover-plate.

FREDERICK SEABERG.
